Patented Nov. 20, 1973

229,323

EXERCISE PERFORMANCE INDICATOR CASING AND DISPLAY

Robert E. O'Brien, 62 Norwald Road,
Arlington, Mass. 02174

Continuation of abandoned design application Ser. No.
17,801, June 23, 1969. This application Mar. 26, 1971,
Ser. No. 128,655

Term of patent 14 years

Int. Cl. D21—02

U.S. Cl. D34—5 K

FIG. 1

FIG. 2

FIG. 3

FIG. 4

FIG. 1 is a perspective view of an exercise performance indicator casing and display embodying my new and ornamental design;

FIG. 2 is a front elevation of FIG. 1;

FIG. 3 is a rear elevation of FIG. 1; and

FIG. 4 is a side elevation of FIG. 1.

This is a continuation of design application Ser. No. D. 17,801, filed June 23, 1969, now abandoned.

I claim:

The ornamental design for an exercise performance indicator casing and display, as shown and described.
